US00D736217S

(12) **United States Design Patent**
Wang

(10) **Patent No.:** **US D736,217 S**
(45) **Date of Patent:** **** Aug. 11, 2015**

(54) **ELECTRONIC DEVICES HOLDER**

(71) Applicant: **Xi-Zhang Wang**, New Taipei (TW)

(72) Inventor: **Xi-Zhang Wang**, New Taipei (TW)

(**) Term: **14 Years**

(21) Appl. No.: **29/470,969**

(22) Filed: **Oct. 25, 2013**

(51) LOC (10) Cl. **08-07**

(52) U.S. Cl.

(57) **CLAIM**

The ornamental design for electronic devices holder, as shown and described.

DESCRIPTION

FIG. 1 is a rear perspective view of an electronic devices holder showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a front perspective view thereof.

Those portions of the illustrated design indicated by broken lines form no part of the claimed design.
